UNITED STATES PATENT OFFICE

JAMES H. MILLHOLLAND, OF PHILADELPHIA, PENNSYLVANIA, ASSIGNOR TO SANDURA COMPANY, INC., OF PAULSBORO, NEW JERSEY, A CORPORATION OF NEW JERSEY

CONTINUOUS-ROLL LABEL

Application filed May 23, 1928. Serial No. 280,044.

My invention relates to piece-goods fabrics which are exposed for sale in rolled or folded packages wherein a corresponding length of folded stripping is included so as to be removable with desired cut-off portions of the fabric in corresponding lengths; and my object is to provide for satisfactorily securing such stripping temporarily to the surface of the fabric while at the same time enabling its very convenient removal after its purpose has been served. The invention is fully described in connection with the accompanying drawing indicating its preferred application, and is clearly defined in the subjoined claims.

15 The drawing is a perspective view of a loosely rolled fabric to which my invention is applied, the outer-end portion thereof being shown unfolded so as to reveal the free hand-grip portion of the pasted strip.

20 The drawing indicates a length of piece-goods 10, such as floor-covering, which is commonly folded closely into a roll for storage or exposure for sale. The label strip 11 is preferably a corresponding length of narrow

25 paper two or three inches wide, which is rolled up with the fabric so as to show upon the exposed surface of the outer layer of the roll; it having printed matter thereon whereby it is adapted to serve as an informative

30 and advertising label upon the otherwise blank surface of the fabric, and also, if desired, as a fabric-measuring means.

In my improved construction, this separately produced paper strip 11, which has im- 35 printed upon its outer surface desired regularly recurring labels or like matter, which recurring labels may be of a length correspond- ing to a convenient unit of measurement and having lines of demarcation there-between so

40 that when laid on the fabric the length thereof may be readily ascertained by counting the number of labels; said strips being also provided on its inner surface with adhesive ma- terial as indicated at 12, the adhesive being

45 placed adjacent one longitudinal edge and extending a distance transversely of the strip only sufficient for effectively attaching the strip to the surface of the fabric with which the strip is associated. The adhesive may be

50 applied in a continuous narrow band along

the edge or at intervals in spots along said edge. The remaining width of the strip as indicated at 13, throughout the length of the fabric, being left free of adhesive so as to only loosely contact with fabric 10 when the strip is rolled up with the latter. The effect of thus securing the strip 11 to the fabric 10 for only a portion of its width, is to insure its satisfactory attachment to the latter for purposes of identification, advertising etc., while at the same time providing for its ready detachment when it is no longer needed or desired. Upon sale of a portion of the roll, the label strip facilitates the unrolling of the proper length, and when such portion is cut-off and flattened out, the unattached edge portion 13 forms a convenient hand-grip by means of which the label strip may be readily detached. This novel feature is of such substantial advantage as to substantially eliminate the difficulty of removal which otherwise makes employment of such desired strips practically unsatisfactory.

What I claim is:

1. A roll of piece-goods fabric having 75 rolled up therewith a like length of label stripping one edge portion of which is provided with an adhesive whereby it is pasted lengthwise to the surface of the fabric and the remaining width-portion of which is free of adhesive throughout its length and provides a loose hand-grip wherever the fabric is straightened out.

2. A measuring label strip to be placed on fabrics, said strip having adhesive applied thereto on a band along one longitudinal edge, the remaining width of the strip being free of adhesive.

3. A measuring label strip to be placed on fabrics, said strip having adhesive applied thereto on a band along one longitudinal edge, the remaining width of the strip being free of adhesive, and matter on said strips serving to calibrate the same.

In testimony whereof I affix my signature. 95

JAMES H. MILLHOLLAND.
